UNITED STATES PATENT OFFICE.

PETER N. MCCHESNEY AND JOHN W. CRAIG, OF WASHINGTON, D. C.

GRAIN-DECORTICATOR.

SPECIFICATION forming part of Letters Patent No. 269,081, dated December 12, 1882.

Application filed September 28, 1882. (No model.)

To all whom it may concern:

Be it known that we, PETER N. MCCHESNEY and JOHN W. CRAIG, of Washington, in the District of Columbia, have invented certain new and useful Improvements in Grain-Decorticators; and we do hereby declare that the following is a full, clear, and exact description thereof, reference being had to the accompanying drawings, and to the letters of reference marked thereon, making a part of this specification.

This invention relates to certain improvements in apparatus for decorticating grain; and it has for its objects to provide for thoroughly stripping and cleaving the grain with great rapidity, as more fully hereinafter specified. These objects we attain by the means described, claimed, and illustrated in the accompanying drawings, in which—

20 Figure 1 represents a longitudinal sectional view of our improved apparatus; Fig. 2, a transverse sectional view on the line $\alpha\alpha$ of Fig. 1, and Fig. 3 a transverse sectional view on the line $\gamma\gamma$ of Fig. 1; and Fig. 4 is a top view of the feed-hopper.

The letter A indicates a rectangular casing, mounted upon suitable legs or supports, B. At one end of said casing is located a fan-chamber, C, which communicates with the interior of the casing by means of an aperture, D, a fan, E, being located therein, and mounted on a longitudinal shaft, F, which is journaled in bearings G H, and provided at one end with a driving-pulley, I.

35 The letter K indicates a series of shafts extending longitudinally through the casing, and having secured to them at equidistant spaces the decorticating-disks L, constructed of corundum or other decorticating material. The 40 said shafts, with their disks, form rotary decorticators, any number of which may be employed, four being represented in the present instance. These are arranged to rotate in the longitudinal cylinders M, located in the casing, 45 the said cylinders being constructed of semi-cylindrical horizontal sections, the lower sections being of perforated sheet metal and the upper sections of reticulated or woven material, as indicated, united together longitudinally in any suitable manner. The upper portions of the cylinders are constructed of woven steel wire and the lower portions of iron perfo-

rated. The object of this is to save expense in the construction, as it has been found in practice that the abrasive action takes place in the upper part of the cylinders principally, and consequently such parts are subjected to greater wear.

The letter N indicates a feed-hopper, which sets upon the top of the casing A, near one end. This hopper is divided by means of a vertical partition, P, having a series of openings, p, near the bottom; the larger compartment being provided with a series of pivoted wings, R, hinged to the partition, which wings are pivoted between bars or strips secured to the hopper N. The said wings, being so arranged, may be shifted laterally, one at a time or all together, in the latter instance the several wings being connected together by means of a suitable rod, for the purpose more fully hereinafter specified. From the narrower compartment extend downwardly the tubes T, which enter the respective longitudinal casings or cylinders near their forward ends, and serve to convey the grain to be decorticated thereto. From the opposite ends of said cylinders extend downwardly the discharge-tubes U V, the tubes U extending between the lower cylinders into the tube V, the tubes V being larger in cross-section than the lower ends of the tubes U, making a common discharge-spout for the two cylinders in vertical line with each other.

The operation of our invention is as follows: The grain is fed into the larger compartment of the hopper, and passes through the openings in the dividing-partition into the smaller compartment, and from thence into the cylinders through the feed-pipes, the flow being regulated by shifting the gates so as to obstruct the passage of the grain to the apertures to a greater or less extent. The grain thus delivered is carried through the cylinders by the combined pressure of the feed or the weight of the incoming grain, which, as it fills the space between two decorticating-disks nearest the feed-tube, overflows into the next space, and so on, and by the rotary action of the decorticators, and as cleaned is discharged through the tubes U and V into a common receptacle. The exhaust mechanism carries off the dust and husks removed from the grain, the tendency being to draw the same into the fan-case and then discharge them.

Having thus described our invention, what we claim as new, and desire to secure by Letters Patent, is—

1. The combination, in an apparatus for decorticating grain, of two or more longitudinal cylinders, constructed of an upper and lower section of woven and perforated material, respectively of steel wire and iron, and the decorticators consisting of a series of spaced disks secured upon shafts, and the feed, discharge, and exhaust mechanism, substantially as and for the purpose specified.

2. In an apparatus for decorticating grain, the combination, with the cylinders and decorticators, of the feed-tubes and the feed-hopper having a partition provided with openings, through which the grain is fed to the tubes, and with wings, whereby the feed of the grain is regulated, substantially as specified.

3. In combination with the upper and lower pairs of decorticating cylinders and the decorticators, substantially as described, adapted to rotate therein, the upper and lower discharge-tubes, the one discharging into the other, as specified.

4. The combination, in a decorticating apparatus, of the inclosing casing having an exhaust-aperture between the cylinders, the exhaust mechanism adapted to draw or suck the loose particles through said aperture, the feed-

hopper and tubes, a series of decorticating cylinders and disks, and the discharge-tubes, the whole constructed substantially as described, and arranged to operate as specified.

5. The combination, in an apparatus for decorticating grain, of a series of decorticating-disks mounted and secured at intervals on a rotating shaft, with a decorticating-cylinder consisting of an upper horizontal section constructed of woven steel wire and a lower horizontal section of perforated sheet-iron, united together, whereby, as herein described, a more durable abrasive surface is obtained where the excess of abrasion occurs, as and for the purpose set forth.

In testimony whereof I affix my signature, in presence of two witnesses, this 13th day of September, 1882.
